UNITED STATES PATENT OFFICE.

CHARLES LEFKOWITZ, ELMER E. ROSS, AND HARRY LUBIN, OF NEWARK, NEW JERSEY.

CARBOY.

1,426,889.

Specification of Letters Patent. Patented Aug. 22, 1922.

Application filed November 12, 1921. Serial No. 514,673.

To all whom it may concern:

Be it known that we, CHARLES LEFKOWITZ, ELMER E. ROSS, and HARRY LUBIN, citizens of the United States, and residents of Newark, in the county of Essex and State of New Jersey, have invented a new and Improved Carboy, of which the following is a full, clear, and exact description.

This invention relates to improvements in carboys, an object of the invention being to provide a carboy, which will effectively cushion the vertical as well as the lateral jolts and jars incidental to the transportation of a large bottle of liquor.

Certain carboys have been invented for a similar purpose, but in nearly all of these patented devices, metal springs or metal parts are employed as a cushioning medium. These patented carboys, therefore, while possessing some merit as carriers for water bottles, are of little or no use as receptacles for bottles of acid, since the acid will quickly corrode any metal with which it comes in contact.

It is an object of our invention therefore to provide a cushioned carboy formed entirely of wood, so that it will be particularly useful for carrying bottles of acid.

A further object is to provide a device of this character, which will be simple and practical in construction, strong, durable and efficient in use, and yet at the same time, comparatively inexpensive to manufacture.

With these and other objects in view, the invention consists in certain novel features of construction and combinations and arrangements of parts, to be more fully hereinafter described and pointed out in the claims.

In the accompanying drawings:

Figure 1 is a top plan view of our improved carboy with the cover removed, the dotted lines indicating the position of a bottle within the carboy;

Figure 2 is a view in vertical section on the line 2-2 of Figure 1;

Figure 3 is a view in side elevation of the carboy;

Figure 4 is a bottom plan view of the cover;

Figure 5 is an edge view of the cover; and

Figure 6 is an edge view of the platform 9.

Referring in detail to the drawings, 1 represents a conventional form of rectangular wooden carboy, which is provided on two

of its sides with outwardly presented rails 2, to facilitate its transportation.

3 represents a flat wooden cover, which is formed with a centrally disposed opening 4 for the accommodation of the neck of a bottle, indicated in dotted lines at 5.

In each inside corner of the carboy, an upright post 6, preferably rectangular in cross section is secured. Two sides of the posts 6 are located against the inner faces of the walls of the carboy and in each of its other two sides, each post is formed with a vertical groove 7. The grooves 7 serve to accommodate the side edges of wooden plates, such as 8. The plates 8 are of some strong light bendable resilient wood and are slideable vertically in the grooves 7. They serve to form a resilient lining for the carboy and to effectively absorb the shock of lateral jolts and jars on the bottle.

It is also necessary to provide means for cushioning the accidental vertical movement of the bottle within the carboy and with this end in view, we provide a resilient platform 9 in the bottom of the carboy. This platform is supported above the floor by a pair of rails, such as 10 and the ends of the platform are located between the posts 6 and serve to support two of the plates 8. The rails 10, preferably include bevelled or tapered floor engaging portions, such as 11, so that when a downward movement of the bottle slightly bows the platform, the rails will slide on the floor of the carboy and prevent breaking or splitting of the platform.

A pair of parallel wooden blocks or strips, such as 12, are secured to the inner face of the cover 3 at opposite sides of the opening 4. The ends of these blocks serve to support a pair of parallel resilient strips 13 in spaced relationship to the cover of the box. These strips 13 are formed with opposed arcuate recesses 14, bevelled as indicated at 15 to conform to the shape of the bottle 5.

It will thus be seen that the plates 8 engage the sides of the bottle to cushion its lateral movement and the platform 9 and strips 13 cooperate to cushion its vertical movement within the container and since all of the cushioning elements, as well as the box itself are made of wood, there is no danger of their becoming inoperative through contact with corrosive acids.

110

Although we have illustrated one of the preferred embodiments of our invention, it will be evident that various slight changes and alterations might be made in the general form and arrangement of the parts described without departing from the invention and hence we do not limit ourselves to the precise details set forth, but shall consider ourselves at liberty to make such slight changes and alterations as fairly fall within the spirit and scope of the appended claims.

We claim:

1. A carboy comprising a rectangular box, a plurality of vertically disposed wooden plates spaced from the walls of the box, and adapted to cushion the lateral movement of a bottle within the box, corner posts within the box having vertical grooves therein, wherein the edges of said plates are slidable.

2. A carboy comprising a rectangular box, a plurality of vertically disposed wooden plates spaced from the walls of the box, and adapted to cushion the lateral movement of a bottle within the box, and means for cushioning the vertical movement of the bottle within the box, said means comprising a resilient platform located in the bottom of said carboy, a pair of inwardly presented resilient strips spaced from the cover of the carboy and adapted to embrace the curved shoulder of a bottle.

3. A carboy comprising a rectangular box, a plurality of vertically disposed wooden plates spaced from the walls of the box, and adapted to cushion the lateral movement of a bottle within the box, and means for cushioning the vertical movement of the bottle within the box, said means comprising a resilient platform located in the bottom of said carboy, a pair

of inwardly presented resilient strips spaced from the cover of the carboy and adapted to embrace the curved shoulder of a bottle, 45 said strips having opposed arcuate recesses therein, and the walls of said recesses being bevelled to conform to the shape of the bottle.

4. A carboy comprising a rectangular box, vertical posts secured in the corners of the box and having aligned grooves therein spaced from the walls of the carboy, resilient plates slidable vertically in the grooves and disposed in parallel relationship to the walls of the carboy, a resilient platform located on the floor of the carboy and supporting two of said plates. 55

5. A carboy comprising a rectangular box, a plurality of resilient wooden plates 60 within the box, means spacing said plates from the walls of the box and permitting vertical movement of the plates, and means for cushioning the vertical movement of a bottle within the box, said means comprising a pair of resilient strips spaced from the cover of the box and engageable with the neck of a bottle in the box and a resilient platform supported above the bottom of the box, a pair of rails supporting the 70 platform, said rails including tapered floor engaging portions adapted to permit sliding movement of the rails when the platform is bowed.

6. A carboy comprising a rectangular box, 75 means for cushioning the lateral movement of a bottle within the box, said means including vertically slidable resilient wooden plates spaced from and parallel with the walls of the box.

CHARLES LEFKOWITZ.
ELMER E. ROSS.
HARRY LUBIN.
